UNITED STATES PATENT OFFICE.

EUGENE L. HOWE, OF CLEVELAND, OHIO.

DESIGN FOR A SNAP-HOOK.

SPECIFICATION forming part of Design No. 21,236, dated December 15, 1891.

Application filed November 17, 1891. Serial No. 412,209. Term of patent 14 years.

To all whom it may concern:

Be it known that I, EUGENE L. HOWE, of Cleveland, Cuyahoga county, Ohio, have invented a new and original Design for Harness-Snaps, of which the following is a full, clear, and exact description, reference being had to the accompanying drawing, which shows in plan view a harness-snap embodying the design.

10 The design consists in a harness-snap having at its rear end a loop of substantially circular outline divided by a cross-piece situate at right angles to the line of the snap-body.

In the drawing, 2 is the snap-body, having

15 at its rear end a loop 3 of substantially circular form. The cross-piece 4 extends across the loop at right angles to the line of the body of the snap and is on the outer side of the center of the loop.

I claim—

20 The design for harness-snaps, substantially as herein shown and described.

Witness my hand, at Cleveland, Ohio, November 11, 1891.

EUGENE L. HOWE.
